WATER GUN

Charles B. Brassington and Bert M. Stibitz,
Mount Carmel, Pa.

Application January 30, 1948, Serial No. 5,376

3 Claims. (Cl. 299—150)

1 The present invention relates to spraying apparatus and more particularly to a water gun for use in wetting coal or other loose material to allay dust and improve working conditions in confined or other areas.

While the gun of the present invention was designed primarily to solve the problems incident to the production and handling of coal, it is to be understood it may have a wide range of use and in discussing its use with coal, the scope of the invention is not to be limited. The problems referred to may be stated as follows:

As coal is produced from the seam it is shot down with explosives and falls away from the face in piles. The amount depends upon the width of the face and the height of the seam. There is dust in the air and in the pile of coal after this operation. There are two problems. One is a spray which will settle and drive out the dust and fumes in the air after the coal has been blown down. The second is to wet the pile of coal so that the dust and the oxides of nitrogen are eliminated when the coal is loaded into mine cars.

In nozzles as heretofore used and particularly those of the fog type, the water capacity is relatively limited and of a short effective range. When the large amounts of coal are blown down it requires a considerable amount of time to wet the coal with a fog nozzle because the capacity is approximately five gallons of water per minute and it requires three gallons of water to wet a ton of coal. Therefore, if there are fifty to ninety tons in a pile a long time is required for wetting. Thus, the fog nozzle or any other nozzles of which applicants have knowledge are not effective for this operation.

Some of the objects of the present invention are to provide an improved water gun; to provide a water gun of rugged construction equipped with a novel nozzle for creating an effective spray for reducing dust and fumes; to provide a spray gun wherein a nozzle functions to pass about twenty gallons of water per minute for efficiently wetting a pile of coal; to provide a spray nozzle unlike conventional nozzles in that it gives a wider range for effective coverage and at such relatively low pressures that the water can be thrown over a thirty foot area; to provide a spray nozzle in association with a nozzle finger tip adjustment; to provide a spray nozzle so shaped and arranged that the cushioning effect of the projected water on the valve seat prevents wear; and to provide other improvements as will hereinafter appear.

2 In the accompanying drawings, Fig. 1 represents a sectional elevation of a spray gun embodying one form of the present invention; Fig. 2 represents a detail in section of the nozzle end of the gun, showing the valve in one open position, the section being on an enlarged scale; Fig. 3 represents an end elevation of the gun viewed from the nozzle end; Fig. 4 represents a side elevation of the valve stem; Fig. 5 represents a side elevation of the control member; Fig. 6 represents an end elevation of the control member; and Fig. 7 represents a rear end elevation of the valve stem.

Referring to the drawings, one form of the present invention comprises an elongated tubular barrel or body 10 having an angularly disposed tubular neck 11, preferably threaded at its free end for coupling the discharge end of a hose (not shown) by which a medium, such as water, is supplied under pressure by way of the conduit 12 to the bore 13 of the barrel 10.

For discharging the incoming water, the bore end of the barrel 10 towards which the angular conduit 12 is directed, is enlarged at a predetermined location to form a circumferential outwardly diverging throat 14, which terminates in a cylindrical passage 15 coaxial with the bore 13. The outer circumferential edge 16 of the passage 15 forms a seat for a valve disc 17 in the form of a truncated segment of a sphere which serves to open and close the passage 15 for positive regulated discharge of water by axial movement of the attached valve stem 18. This regulation is supplemented by a novel discharge nozzle formed by outwardly flaring the discharge end of the barrel 10 to form an annular head 20 having a wall thickness greater than the thickness of the wall of the barrel 10. Internally, the head 20 is cup shaped, thereby providing an arcuate surface 21 complementary to and encircling the convex surface of the valve disc 17, and so dimensioned as to provide a slight clearance between the parts as the valve disc 17 moves away from its closed seating position upon the edge 16. Preferably, the respective radii of the convex and the concave surfaces are described about the same center. Thus, the discharge end of the concave nozzle has a defined convergence which functions to cause a portion of the discharged stream to be directed towards the axis of the discharge. As a result, the working stream comprises a core of fog encircled by a more or less solid cone or fan of water particles. By varying the position of the valve disc 17 within the three-part shaped nozzle, the diameter of

the cone can be altered to meet the particular condition of use; however, the distinct advantage of the nozzle configuration is that it is possible to obtain an effective spray coverage up to fifty feet and at comparatively low water pressures. Furthermore, the radial design of the valve disc and the valve body discharge end protects the valve seat by a cushion of water which prevents wear.

In order to control the valve adjustment, the valve stem 18 is threaded for an appreciable portion of its length (preferably about one half) to traverse a threaded portion 19 of the bore 13, and project exteriorly of the bore 13 by way of a stuffing box or packing gland 22, where it terminates in a reduced square section 23, followed by a further reduced threaded tip 24. Torque is transmitted to the valve stem 18 by means of a cup sleeve 25 of an internal diameter to externally telescope with the outer cylindrical face of the barrel 10, and having its closed end provided with a square hole 26 coaxial with the stem 18. The hole 26 is dimensioned to fit snugly about the square section 23 while allowing the threaded tip 24 to project in order to receive a locking nut 27. By this construction, a finger tip control for regulation of the valve is obtained, and for ease of operation the sleeve surface is preferably knurled. Also, this sensitive finger tip control prevents damage to the valve stem due to rough use.

In operation, the neck 11 is connected by a hose to a suitable source of water under pressure and with the valve disc 17 in closed position no discharge will take place. At the place of use 35 the control sleeve 25 is turned to feed the stem 18 in the direction to lift the valve 17 from the seat 16 and start the stream discharge. The shape and character of the emerging stream can then be adjusted by further finger tip manipulation of the sleeve 25 to thereby alter the relative positions of the convex and concave surfaces and their relation to the two-part throat.

Thus it will be evident that the normal open position of the valve 17 depends upon the water pressure and the type of spray pattern desired. For example, with a fog spray the valve 17 would be practically closed, while if a narrower pattern or greater water capacity is required the valve 17 would be farther away from the seat. Attention is further directed to the novel cylindrical passage 15 which functions to form a cushion of water serving as a means to protect the circumferential seat 16. Also, it causes a more streamlined flow and decreases the friction 55 ordinarily created in prior type nozzles by an abrupt change in direction. Furthermore, the discharge entering the diverging throat is agitated so that the valve is self-cleaning. Thus, pieces of coal, rust, timber chips, and other particles are prevented from clogging the outlet and the use of strainers for this purpose is unnecessary.

Having thus described our invention, we claim:

1. A water gun comprising a tubular casing, a

discharge head on said casing internally contoured to provide successively an expansion throat, a cylindrical passage, and a cup-shaped discharge, said parts forming a unitary nozzle for projecting fog and water, said water being a solid cone encircling said fog, means to introduce water under pressure to the interior of said casing, a valve movably mounted in said discharge, said valve being complementally contoured to seat within said discharge as a closure, and means for actuating said valve, whereby in open position thereof the flow through said discharge can be regulated.

2. A water gun comprising a tubular casing, a discharge head on said casing internally contoured to provide successively an expansion throat, a cylindrical passage, and an annular concave discharge, said parts forming a unitary nozzle for projecting fog and water, said water being a solid cone encircling said fog, means to introduce water under pressure to the interior of said casing, a valve movably mounted in said discharge, said valve being complementally contoured to seat within said discharge as a closure, a stem on said valve threaded within said casing and projecting exteriorly thereof, and means on the projecting end of said stem to turn said stem to open and close said valve, whereby in open position the flow through said discharge can be regulated.

3. In a water gun, the combination of a discharge nozzle formed by a conical outwardly diverging inlet, a concave outlet, and a cylindrical passage intermediate said inlet and outlet, and a valve in the form of a spherical segment having its smaller diameter within said discharge nozzle and disposed toward said inlet, whereby a stream of water is separated into an area of fog encircled by a solid cone.
